United States Patent Office

Des. 191,872
Patented Dec. 5, 1961

191,872

MISSILE LAUNCHER

Charles W. Carter, La Mesa, Wesley E. Woodson, El Cajon, Carl Slyder, Jr., Upland, and Carl L. McKee, Pomona, Calif., assignors to General Dynamics Corporation, San Diego, Calif., a corporation of Delaware

Filed May 24, 1960, Ser. No. 60,713

Term of patent 14 years

(Cl. D30—1)

FIG. 6

FIG. 3

FIG. 4

FIG. 5

FIG. 7

FIGURE 1 is a perspective view of a missile launcher showing our new design;

FIGURE 2 is a side elevational view of the left side thereof;

FIGURE 3 is a top plan view;

FIGURE 4 is a side elevational view of the right side;

FIGURE 5 is a rear end view;

FIGURE 6 is a front end view, and

FIGURE 7 is a bottom plan view of the missile launcher.

We claim:

The ornamental design for a missile launcher, substantially as shown.
